Nos. 1247

A. C. Barstow, of Providence, R. I.
Letters Patent No 1247, dated June 12, 1860.

The schedule referred to in these Letters Patent and making part of the same.

To all persons to whom the presents shall come:

Be it known that I, A. C. Barstow, of Providence, in the County of Providence, and State of Rhode Island, have invented a new and useful design for a Cooking range, and I hereby declare that the said new design is fully described in the following description and represented in the accompanying drawings to which reference is hereinafter made.

The figures of the accompanying plate of drawings represent

Dec. 1247

my new design

Fig. 1. is an elevation of the front plate of the range,

Fig. 2. is a section showing form of mouldings &c, taken in the plane of the line A. B. fig. 1.

Fig. 3. is a section taken in the plane of the line C. D. fig. 1.

The top of the plate is ornamented with the arches a. a. &c, drops b. b. &c, and the bottom with projecting pieces c. c. &c.

The oven doors d. d. have on each of them the raised panels e. e. - e. e. ornamented as and of the shape, shown in the drawings. Near one end of the plate is a raised panel f. f. The ends of the plate are ornamented with scolloped mouldings g. g.

Having thus described my improvement, I shall state my claim as follows:

What I claim as my invention and desire to have secured to me by Letters Patent is the new design for cooking range, consisting of the ornamental configurations as herein described and represented in the drawings.
